UNITED STATES PATENT OFFICE.

OREL D. ORVIS, OF NEW YORK, N. Y.

WATER-TUBE BOILER.

SPECIFICATION forming part of Letters Patent No. 702,670, dated June 17, 1902.

Application filed March 29, 1901. Renewed February 26, 1902. Serial No. 95,680. (No model.)

To all whom it may concern:

Be it known that I, OREL D. ORVIS, a citizen of the United States of America, residing in the borough of Manhattan, New York city, 5 in the county of New York and State of New York, have invented certain new and useful Improvements in Water-Tube Boilers, of which the following is a specification.

My invention has reference to improvements in steam-boilers, and particularly to updraft water-tube boilers, it having for its objects, first, to increase the efficiency of such boilers by thoroughly utilizing the heat of the combustible material; secondly, to provide a rapidly-steaming boiler, and, thirdly, 15 to provide means for producing perfectly dry or superheated steam.

With these objects in view my invention consists, essentially, in a boiler having two vertical drums placed at opposite ends of the furnace and each having a water and a steam space, horizontal headers extending laterally from the said drums and connected by longitudinal tubes, part of which form water-tubes 25 and part form drying or superheating tubes, combined with a furnace having grates adapted to be fired from opposite sides of the front drum and deflecting-walls over the first header extending from the walls of the furnace into proximity to the drums for directing the products of combustion inwardly between the drums.

My invention furthermore consists in connecting the upright water-drums by means 35 of horizontal tubes arranged in vertical tier, combined with deflecting-plates arranged above the first deflecting-walls and adapted to redirect the products of combustion laterally against the water-tubes connecting the horizontal headers.

The nature of my invention will best be understood when described in connection with the accompanying drawings, in which—

Figure 1 represents a longitudinal sectional 45 elevation taken on the line 1 1, Fig. 2 Fig. 2 is a transverse section taken on the line 2 2, Fig. 1. Fig. 3 is a longitudinal section taken on the line 3 3, Fig. 2.

Similar letters and numerals of reference 50 designate corresponding parts throughout the several views of the drawings.

Referring to the drawings, the letters A designate the side walls of a furnace.

B is the front wall, provided with suitable charging-openings b on opposite sides of the 55 center of the furnace and with ash-pit openings c.

C is the rear wall, D the supporting-walls, and E the grates extending from the front wall B to the supporting-walls D and supported by the two walls in the usual manner.

F is a central longitudinal wall extending from the front wall B to the rear wall C and dividing the furnace into two parts on a line 60 with the grate E.

The grates E may extend the entire length of the furnace or throughout only a portion of the same. If the grates extend only through part of the length of the furnace and so necessitate the use of a supporting-wall D, 70 I prefer to close the space between the wall and the rear wall of the furnace by a cover, as D', so as to prevent the fuel from falling back of the wall D.

In the front wall of the furnace is supported a vertical drum G, and in the rear wall is supported a vertical drum H, of greater height than the drum G, and to each of said drums are connected by nipples 1 or other means 75 suitable headers I, extending parallel with the front of the boiler and connected by longitudinal tubes J. These headers extend from the nipples I to near the side walls A of the boiler, just sufficient space being left to permit of expansion of the headers under 80 heat without crowding the walls. The headers I are placed close together and each connected by two tubes J with the header directly opposite, so as to obtain a ready circulation of water in the drums G and H. The top headers I', which are located above the water-line 10 10 of the boiler, are connected by but one set of tubes J', as I find this number of tubes to be sufficient for properly drying 85 or superheating the steam, although it must be understood that any number of headers and connecting-tubes may be used for the purpose, according to the degree of superheating required.

The lower headers I² are 90 preferably connected by one set of tubes J², horizontally arranged, and above the same I place deflecting-walls L, extending inwardly 95 100

from the side walls A to near the drums G and H. The drums G and H are connected by a vertical series of horizontal tubes M, of which one or more of the upper tubes M' may 5 form superheating-tubes, similarly to the tubes J'. Above the horizontal deflecting-walls L are arranged deflecting-walls N, which extend in curved lines from the tubes M to the first set of tubes J, adjacent to the vertical drums G and H, and are supported by the two sets of tubes M and J. Between the corresponding series of tubes at the end of the arched deflecting-plates N are arranged deflecting-plates O, which extend horizontally 10 for a short distance. The grates E preferably extend nearly throughout the length of the furnace, which is made correspondingly short.

R R are the blow-off pipes for the drums. 15 S is the feed-pipe to one of the drums, and T the outlet for steam, and U is the uptake or chimney for the escaping gases connected with the top of the furnace. The products of combustion from the grates E pass in the 20 directions of arrows 11 upwardly against the tubes J', above which are located the deflecting-walls L. These deflecting-walls carry the products of combustion inwardly toward the tubes M, from whence they again are directed 25 outwardly through the series of tubes J by the deflecting-plates N and O, and finally said products are conducted to the uptake U, leading to the chimney by the wall or roof V, located above the upper series of tubes 30 J'. The course of the products of combustion is indicated by arrows 11 in the several figures of the drawings. By tracing these arrows it will be seen that the products of combustion from the grates E meet at the 35 center of the furnace—that is, in the central space terminated at its top by the deflecting-plates N—and this space forms a combustion-chamber where the gases mingle and are broken up in view of the meeting of opposing 40 currents. This combustion-chamber I have designated by the letter W. Above said deflecting-walls N the gases again meet at the center of the boiler and are finally conducted away through the uptake. 45

In order to insure a perfect water circulation, I place in the rear water-drum H a partition Y, which is located at about the center of the drum and provided with a transverse opening 2. The circulation of water takes 50 place as indicated by arrows 12—that is, from the lower part of the drum H through the set of tubes M below the arches N to the front drum G, from thence through the tubes M above the arches N back to the drum H above 55 the partition Y. Circulation also takes place 60 downwardly from the upper part of the drum H in view of the orifice 2 in the partition Y. Circulation furthermore takes place laterally through the headers I and tubes J, as indicated by arrows 12.

While I have herein shown the tubes connecting the headers I and those connecting

the vertical water-drums extending horizontally, it is of course to be understood that they need not be exactly horizontal, although 70 I have found that in a boiler of this construction the circulation of water is practically the same as if the tubes were pitched or angular.

It will be readily understood that the feed-water entering through the feed-pipe S passes twice through the length of the boiler and that the steam generated in the several tubes separates from the water as soon as it is delivered to the drum G and passes upwardly 80 into the steam-space of said drum and from thence through the drying or superheating tubes connecting said drum with the steam-space of the drum H. In view of this arrangement only water enters the upper tubes, 85 and steam is again generated during the passage of the water through the upper series of tubes on its way to the drum H. Since the steam can rapidly disengage from the water in the body of the boiler—that is to 90 say, during the transit of the water through the boiler—a large superficial surface of separation is not essential, and consequently the drums need not be made of large diameter.

What I claim as new is—

1. A water-tube boiler comprising two vertical drums placed at opposite ends of the furnace and each having a water and a steam space, horizontal headers extending laterally from the said drums and connected by longitudinal tubes, part of which form water-tubes and part form drying or superheating tubes, combined with a furnace having grates adapted to be fired from opposite sides of the front drum, and deflecting-walls over the 100 first header extending transversely from the longitudinal walls of the furnace into proximity to the drums for directing the products of combustion inwardly between the drums, substantially as described.

2. A water-tube boiler comprising two vertical drums placed at opposite ends of the furnace and each having a water and a steam space, horizontal headers extending laterally from the said drums and connected by longitudinal tubes, part of which form water-tubes and part form drying or superheating tubes, longitudinal tubes directly connecting the two vertical drums, combined with a furnace having grates adapted to be fired from opposite sides of the front drum, and deflecting-walls over the first header extending from the walls of the furnace into proximity to the drums for directing the products of combustion inwardly between the drums, substantially as described.

3. A water-tube boiler comprising two vertical drums placed at opposite ends of the furnace and each having a water and a steam space, horizontal headers extending laterally from the said drums and connected by longitudinal tubes, part of which form water-tubes and part form drying or superheating tubes, longitudinal tubes directly connecting the two

vertical drums, combined with a furnace having grates adapted to be fired from opposite sides of the front drum, deflecting-walls extending from the walls of the furnace into 5 proximity to the drums for directing the products of combustion inwardly between the drums, and horizontal deflecting-plates located above the deflecting-walls for directing the products of combustion outwardly, substantially as described.

4. A water-tube boiler comprising two vertical drums placed at opposite ends of the furnace and each having a water and a steam space, horizontal headers extending laterally 15 from the said drums and connected by longitudinal tubes, part of which form water-tubes and part form drying or superheating tubes, a combustion-chamber formed between the adjacent ends of the headers and containing 20 longitudinal tubes connecting the two vertical drums, deflecting-walls arranged between the headers and extending from the walls of the furnace to the combustion-chamber, and deflecting-plates extending from the connecting-tubes of the drums to the connecting-tubes of the headers, substantially as described.

5. A water-tube boiler comprising two vertical drums placed at opposite ends of the furnace and each having a water and a steam space, horizontal headers extending laterally 30 from the said drums and connected by longitudinal tubes, part of which form water-tubes and part form drying or superheating tubes, longitudinal tubes directly connecting the two vertical drums, combined with a furnace having grates on opposite sides of the drums, and deflecting-surfaces arranged at different 35 levels for respectively directing the products of combustion inwardly and outwardly with respect to the longitudinal tubes connecting the drums; the lower deflecting-surfaces being arranged between the headers and part of the upper deflecting-surfaces being arranged between the tubes connecting the headers while the remaining parts of said upper deflecting-surfaces extend from the headers to 40 the connecting-tubes of the drums, substantially as described.

6. A water-tube boiler comprising two vertical drums placed at opposite ends of the furnace and each having a water and a steam 45

space, horizontal headers extending laterally from the said drums and connected by longitudinal tubes, part of which form water-tubes and part form drying or superheating tubes, longitudinal tubes directly connecting the two 50 vertical drums, one of said drums being provided with a transverse perforated partition having an opening therein, combined with a furnace having grates on opposite sides of the drums, and deflecting-surfaces arranged at 55 different levels for respectively directing the products of combustion inwardly and outwardly with respect to the longitudinal tubes connecting the drums, substantially as described.

7. A water-tube boiler comprising two vertical drums placed at opposite ends of the furnace and each having a water and a steam space, horizontal headers extending laterally 60 from the said drums and connected by longitudinal tubes, part of which form water-tubes and part form drying or superheating tubes, longitudinal tubes directly connecting the two vertical drums, combined with a furnace having grates on opposite sides of the drums, 65 and deflecting-surfaces arranged at different levels for respectively directing the products of combustion inwardly and outwardly with respect to the longitudinal tubes connecting the drums; the lower deflecting-surfaces being arranged between the headers and part of the upper deflecting-surfaces being arranged between the tubes connecting the headers while the remaining parts of said upper deflecting-surfaces extend from the headers to 70 the connecting-tubes of the drums, substantially as described.

In testimony whereof I have hereunto set my hand in the presence of two subscribing witnesses.
